CLAIM

The ornamental design for a case for electronic communication device, as shown and described.

DESCRIPTION

FIG. 1 is a front, left, and top perspective view of a case for electronic communication device showing my new design in an open configuration;

FIG. 2 is a rear, right, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the case for electronic communication device in a closed configuration, with the hinge pen holder portion shown in an open position, and where an unclaimed environmental pen feature is shown separated from the case for electronic communication device;

FIG. 10 is an opposite side exploded perspective view of the case for electronic communication device in a closed configuration, with the hinge pen holder portion shown in an open position, and where an unclaimed environmental pen feature is shown separated from the case for electronic communication device; and,

FIG. 11 is an exploded perspective view of the case for electronic communication device in a closed configuration, and where an unclaimed environmental pen feature is shown separated from the case for electronic communication device.

The das-dash broken lines in the drawings represent portions of the case for electronic communication device or environmental subject matter that form no part of the claimed design.
